CARBURETOR

Harmon H. Earle, Flint, Mich.

Application June 6, 1933, Serial No. 674,572

1 Claim. (Cl. 261—51)

This invention appertains to new and useful improvements in carburetors, such as are commonly employed in conjunction with internal combustion engines.

5 The principal object of the present invention is to provide means for progressively admitting the charge to the intake manifold in proportion to the speed thereof.

Another important object of the present invention is to provide a novel form of charge admitting means, wherein the suction of the engine will act to open additional fuel communication with the intake manifold as a supplement to the intake through the low speed inlet.

15 Another important object of the invention is to provide means whereby the air and fuel are thoroughly mixed at the carburetor.

These and various other important objects and advantages of the invention will become apparent to the reader of the following specification.

In the drawings:—

Figure 1 represents a vertical sectional view through the novel carburetor.

25 Figure 2 represents a vertical sectional view through the novel carburetor, this view showing the high speed valve controlling means in section.

Figure 3 represents a horizontal sectional view taken substantially on line 3—3 of Figure 2.

Figure 4 represents a perspective view of the adjusting means for the high speed valve.

Figure 5 represents the bail employed with the high speed valve.

35 Figure 6 represents a perspective view of the tube.

Figure 7 represents a perspective view of the valve stem.

Figure 8 represents a perspective view of the 40 valve needle.

Referring to the drawings wherein like numerals designate like parts, it can be seen in Figure 1 that numeral 5 represents the carburetor casting which is provided with the upwardly extending pipe section 6 within which the high speed fuel valve operating mechanism, generally referred to by numeral 7, is located, and with the horizontally disposed neck 8 open at its outer end and having the air passage controlling 50 butterfly valve 9 operative therein. At the opposite side of the casting 5 from the neck 8 is the shell 10 of the float chamber, the same having the removable cap 11 and the float 12 operative therein for regulating the fuel inlet valve 13 which has a connection 14 whereby the usual

fuel feed line (not shown) can be connected to this shell 10.

The bottom of the casting 5 is provided with a thickened portion 15 in which is located the bore 16 plugged at one end, as at 17, while its opposite end communicates with the interior of the shell 10 by way of a small duct 18.

The casting 5 has a horizontal partition 19 therein, this partition having an opening 20 into which the upper end of the valve shell 21 60 terminates and also a large opening having the feed ring 22 therein.

The low speed valve stem 21 is provided with a threaded head 23 at its lower end for threaded disposition into a threaded bore in the thickened portion 15. This stem 21 has an opening 24 therein at the point thereof traversing the bore 16, so that fuel can enter the stem and the outlet of this fuel from the stem is regulated by the needle valve 25 which extends longitudinally 75 through the stem 21 and which has its lower end bent laterally, as at 26, to form a handle whereby the said needle valve can be adjusted.

As is clearly shown in Figure 2, a high speed valve stem 27 has its lower end threaded, as at 28, and disposed into the thickened portion 15 so that the interior of the stem is in communication with the said bore 16. The lower portion of the thickened portion 15 has a threaded opening therethrough which is normally closed 85 by a screw 29 and through this opening the lower portion of the stem 27 can be reached by a tool or some suitable instrument, if desired, for any purpose.

The feed ring 22 supports and preferably has 90 secured thereto the upstanding conical ring 30 through which the tube 31 extends, this tube being provided with a flared upper end portion 31^a and will rest upon the uppermost convolution of the spring 30. The lower end of the 95 tube 31 is cut off at an angle, as shown at 31^b and terminates a substantial distance upwardly from the thickened portion 15 of the carburetor casting.

Disposed upon the upper end of the tube 31 100 is the cylindrical coiled spring 32 which has a cap plate 33 through which extends the threaded member 34 which has a head 35 at its lower end bearing against the bottom side of the said cap plate 33. Jamb nuts 36 on the threaded member 34 are employed to bind against the cap plate 33 at its top to maintain the head 35 snugly against the bottom of the plate 33 and this head is apertured to receive the upper eye 37 of the link 38 which also has an eye 39 at its 110

lower end disposed through the opening 40 at the upper end of the needle valve 41 which operates within the valve stem 27, as clearly shown in Figure 2.

5 As is clearly shown in Figure 3, the upstanding pipe section portion 6 of the carburetor casting has an offset portion 42 through which the short shaft 43 is journaled, this shaft being provided with a pair of openings 44 through which 10 the bight portion of the bail 45 is trained. The end portions of this bail 45 are bent inwardly to provide trunnions 46-46 which can be sprung into corresponding openings in the flared upper end portion 31^a of the tube 31, as 15 in the manner substantially shown in Figures 1 and 3.

This shaft 43 is provided with an arm 47 in one end and interposed between the outer end of this arm and some stationary structure, such 20 as a portion of the carburetor casting, is a coiled expandible spring 48.

The spring 48, bail 45 and associated details are employed to control the tension on the spring 30 which is adapted to withstand considerably more suction than the spring 32.

Obviously, in the operation of this device at low speed, the suction in the manifold will only be sufficient to draw fuel from the low speed valve stem 21. However, as the speed increases 30 and the suction proportionately increases, action takes place on the spring 32 and cap plate 33 which causes an expansion of the spring 32 and this, of course, gives a lifting action to the needle valve 41, besides spacing 35 the convolutions, so that air is sucked through the tube 31 and mixes therein with the fuel sucked from the stem 27 and this air and fuel in passing between the convolutions of the spring 32, becomes thoroughly mixed.

40

As the suction action increases further, the spring 30 is acted upon and this, of course, lifts upwardly on the tube 31 and in elevating the spring 32, causes a greater lift of the needle valve 41, thus opening the valve stem 27 further to permit a greater inlet of fuel.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

In a carburetor, a shell having an air inlet and a mixed fuel outlet, a fuel conduit, a tube extending from the conduit into the mixed fuel outlet, a frusto-conically shaped spring having its convolutions normally closed and being interposed between the inner side of the shell at the mixed fuel outlet, a tube provided with a flared end, said tube being supported by the reduced end of the frusto-conically shaped spring by its flared end and being adapted to project inwardly to telescope the tube extending from the fuel conduit, a needle valve in the outer end of the fuel tube, a plate, a linked connection between the plate and the needle valve, and a normally closed extensible coiled spring interposed between the plate and the flared end of the first mentioned tube, said plate being adapted to be acted upon by the usual engine suction to extend the spring so that fuel and air can pass outwardly of the last mentioned spring, the first mentioned spring being adapted to be acted upon by the increased suction of the engine operating at high speed to admit a greater volume of air.
